UNITED STATES PATENT OFFICE.

BENJAMIN F. WHEELER, OF DETROIT, MICHIGAN, ASSIGNOR TO THE
WHEELER SADDLE COMPANY, OF SAME PLACE.

DESIGN FOR A SADDLE-BASE.

SPECIFICATION forming part of Design No. 29,989, dated January 10, 1899;

Application filed December 16, 1898. Serial No. 699,507. Term of patent 7 years.

To all whom it may concern:

Be it known that I, BENJAMIN F. WHEELER, a citizen of the United States, residing at Detroit, in the county of Wayne, State of Michigan, have invented and produced a new and original Design for a Base for a Bicycle-Saddle; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to a new and original design for a base for a bicycle-saddle.

In the accompanying drawings, Figure 1 is a perspective view of my design for a saddle-base. Fig. 2 is a plan view thereof. Fig. 3 20 is a transverse section on line 3 3 of Fig. 2. Fig. 4 is a side elevation.

The leading feature of my design consists in the seat or base portion of the saddle, comprising a narrow forwardly-extending neck 25 and a broad flaring rear portion divided by an oblong oval-shaped opening extending forward through the back of the base, the seat

portion of the base being hollowed or rounded out and the rear edge thereof curved sharply upward, so as to stand high above the plane 30 of the seat portion of the base to form a figure having two rearwardly-flaring members whose rear edges curve upwardly and stand in a plane nearly at right angles to the forwardly-projecting portion of the figure. 35

A designates the saddle-base; B, the reduced forwardly-extending neck portion; C, the oblong oval opening, extending forward through the back of the base; D, the hollowed seat portion of said base, and E the upwardly-turned rear margin of said figure, the whole presenting to the eye a harmonious and ornate figure, as shown in the drawings.

Having described my design, what I claim is— 45

The design for a saddle-base substantially as herein shown and described.

In testimony whereof I sign this specification in the presence of two witnesses.

BENJAMIN F. WHEELER.
